STACKED ELECTRODE ASSEMBLY FOR
ELECTRON DISCHARGE DEVICESWilliam S. Brian, Owensboro, Ky., assignor, by
mesne assignments, to General Electric Com-
pany, a corporation of New York

Application October 4, 1944, Serial No. 557,126

34 Claims. (Cl. 250—27.5)

1

This invention relates to electron discharge devices and, while it is of general application, it is particularly suitable for embodiment in devices of the type to be operated at high frequencies or ultra-high frequencies and to devices of the duplex or dual-purpose type. The invention also relates to an electrode assembly of general application but which is particularly suitable for use in the devices of the invention.

Heretofore general purpose vacuum tubes adapted for mass production methods at relatively low cost have been manufactured in large quantities. These tubes, however, have not been suitable for many applications. For example, special designs have been made for the purpose of minimizing lead in impedance and interelectrode admittance to render the tubes more suitable for high frequency operation. Miniature tubes have been employed for applications where space requirements are important. The special purpose tubes, however, have not, on the whole, been well adapted for mass production and the designs, while improving certain characteristics of the general purpose tubes, have offered no advantage with respect to others. In accordance with the teachings of my invention, I provide an improved electrode assembly and discharge device which is well suited for a wide variety of applications and which is at the same time well adapted for mass production methods.

It is an object of the invention, therefore, to provide a new and improved electron discharge device which is simple and inexpensive in construction and readily adapted to mass production by automatic machinery and one which overcomes one or more of the above mentioned shortcomings and limitations of the general purpose tubes of the prior art.

It is another object of the invention to provide a new and improved electron discharge device which incorporates all or substantially all of the advantageous characteristics of the several special purpose tubes of the prior art and yet one which is of low cost and suitable for mass production by automatic machinery and for use as a general purpose tube.

It is another object of the invention to provide a new and improved electrode assembly which is of general application but which is particularly suitable for use in the new and improved electron discharge device of the invention.

In accordance with the invention, there is provided an electron discharge device comprising an electrode assembly having a plurality of electrode connections and an annular sealing member or stem surrounding the assembly and including a plurality of radial lead-in conductors sealed

2

therin. The lead-in conductors are connected to the electrode connections and there is provided means enclosing opposite sides of the electrode assembly and sealed to opposite sides of the stem.

Further in accordance with the invention, the electrode assembly incorporated in the electron discharge device described comprises a cathode structure including a cathode and a member surrounding the cathode and having peripheral supporting provisions and a cylindrical shell of insulation material engaging the supporting provisions. The electrode assembly also includes a plurality of spacer rings of insulation material stacked upon the member within the shell and control electrode means supported between predetermined adjacent ones of the spacer rings. The assembly also includes means for retaining the spacer rings and the control electrode means within the shell.

Further, in accordance with the invention, the cathode of the electrode assembly is of the equipotential type and comprises an annular hollow conductive member having an electron emissive coating on at least a portion of the surface thereof and a heating element disposed within the member.

Further, in accordance with the invention, each of the control electrodes of the assembly of the invention comprises an annular metallic supporting member, a wire screen covering the opening in the member and bonded to the periphery thereof, the screen having a dish-like configuration with a substantially plane bottom.

Further, in accordance with the invention, the sealing stem or lead-in sealing member for the electron discharge device comprises an annular member of fusible vitreous material formed with a plurality of deep radial slots in one face thereof, and a lead-in conductor disposed in each of the slots, the slots in the member being closed by the application of heat and pressure to the member to fuse the member to the conductors.

The terms "cylindrical" and "annular" are used herein and in the appended claims in their generic sense and are not confined to configurations of circular cross sections.

For a better understanding of the invention, together with other and further objects thereof, reference is had to the following description taken in connection with the accompanying drawings while its scope will be pointed out in the appended claims.

Referring now to the drawings, Fig. 1 is an enlarged cross-sectional detail of a complete electron discharge device embodying the invention; Fig. 2 is an exploded perspective view of the cath-

ode member of the electrode assembly of the device of Fig. 1; Fig. 3 is a perspective view of a control electrode member suitable for embodiment in the device of Fig. 1; Fig. 4 is a perspective view of the anode of the electrode assembly of the device of Fig. 1; Fig. 5 is a plan view of the complete cathode structure of the electrode assembly of the device of Fig. 1; Fig. 6 is a perspective view of the sealing stem of the device of Fig. 1 at an intermediate stage in its fabrication; Fig. 7 is an elevational view, partly in section, of the device of Fig. 1; Fig. 8a is a longitudinal view, partly in section, of a modified form of electron discharge device of Fig. 1 suitable for use as a pin-base type of device; Fig. 8b is an end view of the device of Fig. 8a, and Fig. 9 is a perspective view of an alternative form of anode suitable for use in the device of Figs. 8a and 8b.

Referring now to the several figures of the drawing, there is illustrated an electron discharge device embodying the invention and comprising a novel unitary electrode assembly disposed in a novel form of envelope, together with provisions for making external connections to the electrodes and a novel stem or seal. The electron discharge device of the invention comprises an elongated cylindrical unitary electrode assembly 10, Fig. 1, which may be either of the single electron stream type or, as illustrated, of the duplex type comprising two independent electron discharge paths.

The electrode assembly 10 includes a cathode structure 11, Fig. 5, of any suitable type, preferably comprising an electron emissive cathode member 11a of the equipotential type shown more clearly in the perspective view of Fig. 2. The cathode member 11a is in the form of an annular hollow conductive member formed of two opposed annular trough-like elements 11b and 11c, shown as opened like a clam shell in Fig. 2. The elements 11b, 11c have an electron emissive coating of any well-known type on at least a portion of the surfaces thereof, preferably on only the upper and lower faces thereof. A heating element 11d is disposed within the cathode member 11a and is preferably constructed as an extended non-inductive bifilar insulated helical winding 11d. The wire forming the heating element 11d may be coated with an insulating composition before winding or the winding may be coated after it is wound. The winding 11d is of the same diameter as the maximum inner diameter of the cathode member 11a and, after winding and coating, it may be collapsed axially to fit into the member 11a. An insulating coating suitable for the heating element 11d may be finely divided magnesia or alumina in a nitro-cellulose binder and the coating should be made as thin as practicable in order to minimize the thermal lag of the heating element. The winding 11d is provided with terminals 11e which project from the cathode member 11a through a radial conduit formed by the opposed trough-like radial extensions 11f, 11g formed in the periphery of the elements 11b, 11c, respectively. The elements 11b and 11c may be electrically connected to form a unipotential cathode member, or they may be separated by a film, coating, or layer of insulation material to provide two electrically isolated cathode members each of the equipotential type. With this construction, two electrically independent electron discharge devices may be provided as described hereinafter.

The cathode member 11a is also provided with a plurality of radially extending supporting tabs 11h formed at the rims of the members 11b and

11c and adapted to be fastened together to secure the several elements of the cathode member, as by riveting, welding or otherwise bonding. This annular cathode construction has the advantages of rigidity and substantial freedom from warping of the coated faces thereof, thus aiding in accurately maintaining the desired electrode spacings.

The cathode structure 11 also includes an annular supporting element surrounding the member 11a and thermal expansion means 11i for supporting the member 11a from the annular element. Specifically, the annular element comprises a pair of opposed annular members 11i, 11i surrounding the cathode member 11a and a plurality of semi-rigid or deflectable wires 11j welded or otherwise bonded to the tabs 11h and disposed between and welded or otherwise bonded to both of the members 11i. This semi-rigid support of the cathode member 11a permits relative expansion and contraction between the member 11a and the supporting element without warping of either. The opposed members 11i comprise opposed peripheral supporting means or retaining flanges for the electrode sub-assemblies to be described. Such supporting means may be either internal or external to the sub-assemblies to be supported and may be in the form of tabs, lugs, or the like or, as illustrated, in the form of peripheral opposed rims so that the members 11i, 11i are essentially cup-shaped members with their central portions deleted.

In the duplex type of tube illustrated in Fig. 1, there is provided a pair of electrode sub-assemblies disposed on the opposite sides of the cathode structure 11, each comprising a plurality of elements which may be identical and therefore are identified by the same reference numerals, one set being primed to distinguish it from the other. Each of these electrode sub-assemblies comprises a cylindrical shell 12 of insulation material provided with a connection aperture such as a longitudinal slot 12a. The shell 12 is preferably formed of ceramic material such as steatite or an alumina-silica-magnesia compound of the type commercially available as "Alsimag." The shell 12 engages the peripheral supporting provisions of the cathode structure 11, that is, it is seated in and frictionally engages the cup-shaped member 11i.

The electrode assembly also includes a plurality of identical interchangeable spacer rings 13 and a spacer ring 14, all preferably a ceramic of the same type as the shell 12, stacked upon the member 11i of the cathode structure within the shell 12 and loosely fitting within such shell. Between predetermined adjacent ones of the spacer rings 13 and 14 are supported control electrode means, preferably a plurality of control grids or electrodes 15, 16 and 17, which are supported between each adjacent pair of rings. In case the supporting rings of the electrodes 15, 16, and 17 are coated with a film or layer of insulating material, the spacer rings 13 and 14 need not be formed of insulation material. The outer ring 14 is somewhat wider than the rings 13 in the specific structure illustrated to facilitate spacing the electrodes by the desired amounts.

The control electrodes 15, 16 and 17 may be identical but are preferably of different designs best suited to the particular functions thereof. In the particular tube illustrated, these control electrodes normally comprise a control grid, a screen grid and a suppressor grid. The construc-

tion of each of the control electrodes is best shown in Fig. 3, which may represent, for example, the control electrode 15. This control electrode comprises an annular metallic supporting member 15a having a curved inner rim 15b projecting from one face thereof. A grid of parallel grid wires or, as illustrated, a wire screen 15c of the desired mesh for the particular control electrode under consideration is deformed by a suitable die into a dish-like configuration and is then placed over the ring 15a to cover the opening therein and is welded, hard-soldered or otherwise bonded thereto around the periphery thereof. The deformed portion of the screen 15c extends through the rim 15b and, in the specific type of tube structure illustrated, has a plane bottom of an accurately predetermined depth below the upper face of the member 15a and in a plane parallel thereto, as clearly shown in Figs. 1 and 3.

The depths of the several control electrodes are so related to the width of the spacer rings 13 as to determine accurately the desired spacing between the control electrode 15 and the cathode member 11a and between the control electrodes 15, 16 and 17. Generally, the control electrodes have different depths and are formed with tapered sides to permit them to nest within each other, thereby providing electrode spacings much less than and independent of the width of the spacer rings 13. For example, in the structure illustrated it is seen that the spacing between the control electrode 15 and the cathode member 11a is very small and is an extremely small fraction of the width of the spacer member 13, this very close spacing imparting a very high mutual conductance characteristic to the device. Similarly, by nesting of the grid 16, which may be the screen grid, within the grid 15, the spacing of these two grids may be made small. On the other hand, by inverting the outer control electrode 17, which may be the suppressor electrode, it may be widely spaced from the other control electrodes but disposed closely to the anode, which is the desired relationship. At the same time, the spacer rings 13 are of a substantial width so that they have a reasonable structural strength and are all of the same width, thus making them interchangeable and minimizing the number of forming dies required in their molding.

The control electrodes 15, 16, and 17 are provided with connector means such as the connectors 15d, 16d and 17d, respectively, extending through the slot 12a in the shell 12. As shown in Fig. 1, the two shells have their slots diametrically opposed and each group of electrodes has its electrode connections extending through its respective shell aperture or slot, thus obtaining a maximum spacing between the electrode connections of the two groups of electrodes and minimizing the coupling therebetween.

The electrode assembly also is provided with means for retaining the spacer rings 13 and 14 and the several control electrodes within the shell 12. In the preferred embodiment, this means is a disk-like anode 18 disposed within the shell 12 beyond the several control electrodes and including provisions for engaging the shell to retain such elements therein, for example, a plurality of radially extending upwardly bent tabs 18a adapted frictionally to engage the internal periphery of the shell 12. The configuration of the anode 18 is best shown in Fig. 4 from which it is

seen that it is formed with an annular stiffening groove 18b connected with three radial stiffening grooves 18c. Supported from the center of the anode 18 and within the stiffening groove 18b is a rigid terminal or split eyelet 18d welded or otherwise bonded to the anode for receiving a terminal connection and constituting a support for the electrode assembly. Thus anode 18 comprises means for retaining the several elements of the assembly in their proper relative position while the electrode assembly is retained in position by the frictional engagement of the shell 12 by peripheral rim of the cathode member 11i. The anode is also formed with a plurality of upwardly punched louvers 18e to facilitate exhausting and cooling the interior of the electrode assembly.

The electron discharge device of the invention also includes an annular sealing member 19 surrounding the electrode assembly 10 with the axis of the assembly disposed generally along a diameter of the annular member. The sealing member 19 is preferably in the form of an annulus of fusible vitreous material and formed with a plurality of deep radial slots 19a in one face thereof, as illustrated in Fig. 6. A lead-in conductor 20 is disposed in each slot and the slots are then closed by the application of heat and pressure to the member 19 to fuse the member 19 to the conductors 20 and form a vacuum-tight seal. The electrode connections 15d, 16d and 17d are connected to the radial lead-in conductors 20, preferably the electrode connections of each electrode sub-assembly or space-discharge path 35 being connected to the ones of the lead-in conductors 20 extending through the side of the stem 19 adjacent its respective connection aperture 12a or 12a', as indicated in Fig. 6, while the cathode terminals 11e may be connected to any appropriate ones of the conductors 20. Further, the electrode connections may be so disposed and connected to such lead-in conductors that the screen and suppressor connections are interposed between and tend to shield desired ones of the control grid, cathode and anode connections, thereby minimizing the inter-electrode capacitances of the device. The connections 15d, 16d and 17d may be of flexible metallic ribbon, such as nickel, welded or otherwise bonded to the rims of their respective electrodes. It will be noted that the connections from the rigid anode terminals 18d to their respective lead-in conductors 20 constitute the sole support of the electrode assembly 10 from the sealing stem 19.

The electron discharge device also includes means, preferably a pair of generally hemispherical metallic shells 21 enclosing opposite sides of the electrode assembly and sealed to opposite sides 60 of the member 19, as indicated in Fig. 1, and forming with the member 19 the envelope of the device. The shells 21 are formed of material having a coefficient of thermal expansion matching that of the glass member 19; for example, the member 19 may be formed of a lead-silica glass having a high lead content while the shells 21 may be formed of a ferro-chrome alloy containing 25% to 35% chromium.

While it will be apparent to those skilled in the art that the physical dimensions of the electron discharge device of the invention will vary within wide limits in accordance with the particular performance characteristics required, there follow the dimensions of one electrical discharge

device embodying the invention and designed for use as a radio-frequency amplifier:

	Inches
Outer diameter, member 19	1.500
Overall height	1.187
Shell 12:	
Outer diameter	0.660
Width	0.325
Thickness of shell	0.040
Spacer rings:	
Outer diameter	0.565
Width	0.050
Thickness	0.075
Cathode member 14a:	
Outer diameter	0.300
Inner diameter	0.200
Thickness	0.030
Control electrode 15—depth	0.037
Control electrode 16—depth	0.080
Control electrode 17—depth	0.037
Spacings:	
Control grid 15—screen 16	0.013
Screen 16—suppressor 17	0.167
Suppressor 17—anode 18	0.038

The electron discharge device described may be fabricated in any desired manner but it is preferably constructed in accordance with the method disclosed and claimed in my copending application entitled Method of and apparatus for manufacturing electron discharge devices, Serial No. 564,768, filed November 23, 1944, which issued on June 24, 1947, as United States Patent No. 2,422,945, and assigned to the same assignee as the present application.

In devices in which the spacing between the screen electrode and the anode is not critical, as in the case of beam-power tubes, the anode 18 of Fig. 1 may be omitted and the electrode assembly arranged with respect to the enclosing envelope so that the envelope itself may constitute the anode for the electrode assembly, thus improving the heat-dissipating properties and increasing the power capacity of the device. Such an arrangement may be embodied in a structure of the type represented in Figs. 8a and 8b. The electrode assembly 30 of this form of the invention may be similar to that of Fig. 1 except that the connection slots 12a and 12a' are in alignment and except that the anode 18 is omitted and replaced by a retaining element or ring 31, Fig. 9. The retaining ring 31 is provided with projecting tabs 31a for frictionally engaging the internal periphery of the shell 12 to retain several spacer rings and control electrodes within the shell. It is also formed with a plurality of stiff radial spokes 31b which are joined at the center thereof and support a rigid supporting terminal 31c for connection to a lead-in conductor 32, which may or may not be an electrical terminal of the device. The supporting lead-in conductors, as well as the electrode lead-in conductors 33, are sealed in a suitable stem or sealing base 34, the slots in the shells of the electrode assembly 30 opening in the same general direction, being directed downwardly toward the base 34 to minimize the lengths of the lead-in conductors. In this type of construction the outer shells 12 may, if desired, be made as a single continuous slotted shell instead of in two parts, the cathode supporting ring being constructed similar to the grid-supporting ring and engaged between adjacent spacer rings within the retainer shell.

The assembly 30 is enclosed in a metallic en-

velope or casing 35 sealed at its open end to the periphery of the stem or base 34. It will be understood that the modification of Figs. 8a and 8b may include any desired arrangement of lead-in conductors and may, if desired, be provided with a conventional pin base (not shown) for mounting.

The operation of the improved electron discharge devices illustrated and described above is conventional and need not be described in detail. However, it is seen that this form of electron discharge device has the desirable characteristics of the several special purpose devices of the prior art; that is, the various electrodes of the device and their supporting elements are such as to produce an extremely rigid structure capable of withstanding substantial shock or vibration without damage and without substantially altering the physical spacings of the elements or electrical characteristics of the device. At the same time the spacings between the cathode and the first control electrode and between the several control electrodes may be accurately predetermined at very small values, imparting a very high mutual conductance and accurately reproducible characteristics. At the same time, due to the short lead-in conductors and electrode connections, the inherent impedance of the lead-in conductors and electrode connections is reduced to a minimum. Due to the complete shielding of the inner control electrode from the anode, the capacitance between these elements is a minimum. Also the volumetric displacement of the device is much less than prior art general purpose vacuum tubes. At the same time the sealing structure is extremely simple and the whole assembly operation is one which can be accomplished readily on a mass production basis by assembly line methods as described and claimed in my aforesaid copending application. Because of its adaptability to mass production, the electron discharge device of the invention is capable of extremely low cost production and therefore capable of use as a general purpose vacuum tube, although combining the advantageous characteristics of the several special purpose tubes of the prior art.

While there have been described what are at present considered to be the preferred embodiments of the invention, it will be apparent to those skilled in the art that various changes and modifications may be made therein without departing from the spirit or scope of the invention.

What is claimed as new is:

55. 1. An electron-discharge device comprising, a unitary electrode assembly having a plurality of electrode connections including rigid terminals at opposite ends thereof, an annular sealing member surrounding said assembly and including a plurality of radial lead-in conductors sealed therein, said conductors being connected to said electrode connections, said lead-in conductors connected to said rigid terminals constituting the sole support of said electrode assembly, and means enclosing opposite sides of said electrode assembly and sealed to opposite sides of said member.
60. 2. An electron-discharge device comprising, a unitary duplex electrode assembly having a plurality of electrode connections including an anode at each end thereof and a rigid terminal connected thereto, an annular sealing member surrounding said assembly and including a plurality of radial lead-in conductors sealed therein, said conductors being connected to said elec-

trode connections, said lead-in conductors connected to said rigid terminals constituting the sole support of said electrode assembly, and means enclosing opposite sides of said electrode assembly and sealed to opposite sides of said member.

3. An electron-discharge device comprising, a duplex electrode assembly including two groups of electrodes, a ceramic shell surrounding each of said groups, said shells having diametrically opposed connection apertures therein, and a plurality of electrode connections for each of said groups of electrodes extending through one of said apertures, an annular sealing member surrounding said assembly and including a plurality of radial lead-in conductors sealed therein, each of said plurality of electrode connections being connected to the ones of said conductors extending through the side of said member adjacent its respective aperture, and means enclosing opposite sides of said electrode assembly and sealed to opposite sides of said member.

4. An electron-discharge device comprising, an electrode assembly having a plurality of electrode connections, an annular sealing member surrounding said assembly and including a plurality of radial lead-in conductors sealed therein, said conductors being connected to said electrode connections, and a pair of metallic shells enclosing opposite sides of said electrode assembly and sealed to opposite sides of said member.

5. An electron-discharge device comprising, an electrode assembly having a plurality of electrode connections, an annular sealing member surrounding said assembly and including a plurality of radial lead-in conductors sealed therein, said conductors being connected to said electrode connections, and a pair of generally hemispherical metallic shells enclosing opposite sides of said electrode assembly and sealed to opposite sides of said member.

6. An electron-discharge device comprising, an electrode assembly having a plurality of electrode connections, an annular sealing member surrounding said assembly and including a plurality of radial lead-in conductors sealed therein, said conductors being connected to said electrode connections, and a pair of metallic shells enclosing opposite sides of said electrode assembly and sealed to opposite sides of said member and serving as anode means for the device.

7. In an electron-discharge device, a unitary electrode assembly comprising, a cathode structure including a cathode and a member surrounding said cathode and having peripheral retaining means, a cylindrical shell of insulation material engaging said retaining means, a plurality of spacer rings stacked upon said member within said shell, electrode means supported between predetermined adjacent ones of said spacer rings, and means for retaining said spacer rings and said electrode means within said shell.

8. In an electron-discharge device, a unitary electrode assembly comprising, a cathode structure including a cathode, an annular member having peripheral retaining means, thermal expansion means supporting said cathode from said member, a cylindrical shell of insulation material engaging said retaining means, a plurality of spacer rings stacked upon said member within said shell, electrode means supported between predetermined adjacent ones of said spacer rings, and means for retaining said spacer rings and said electrode means within said shell.

9. In an electron-discharge device, a unitary

electrode assembly comprising, a cathode structure including a cathode, an annular member having peripheral retaining means, a plurality of deflectable supporting wires bonded to said cathode and to said member, a cylindrical shell of insulation material engaging said supporting provisions, a plurality of spacer rings stacked upon said member within said shell, electrode means supported between predetermined adjacent ones of said spacer rings, and means for retaining said spacer rings and said electrode means within said shell.

10. In an electron-discharge device, a unitary electrode assembly comprising, a cathode structure including a cathode and an annular cup-shaped member surrounding said cathode, a cylindrical shell of insulation material seated in and frictionally engaging said cup-shaped member, a plurality of spacer rings stacked upon said member within said shell, electrode means supported between predetermined adjacent ones of said spacer rings, and means for retaining said spacer rings and said electrode means within said shell.

15. 11. In an electron-discharge device, a unitary electrode assembly comprising, a cathode structure including a cathode and a member surrounding said cathode and having peripheral retaining means, a longitudinally slotted cylindrical ceramic shell engaging said retaining means, a plurality of spacer rings stacked upon said member within said shell, electrode means supported between predetermined adjacent ones of said spacer rings and provided with connector means extending through the slot in said shell, and means for retaining said spacer rings and said electrode means within said shell.

12. In an electron-discharge device, a unitary electrode assembly comprising, a cathode structure including a cathode and an annular cup-shaped member surrounding said cathode, a longitudinally slotted cylindrical ceramic shell seated in and frictionally engaging said cup-shaped member, a plurality of spacer rings stacked upon said member within said shell, electrode means supported between predetermined adjacent ones of said spacer rings and provided with connector means extending through the slot in said shell, and means for retaining said spacer rings and said electrode means within said shell.

17. 13. In an electron-discharge device, a unitary electrode assembly comprising, a cathode structure including a cathode and a member surrounding said cathode and having peripheral retaining means, a cylindrical shell of insulation material engaging said retaining means, a plurality of spacer rings stacked upon said member within said shell, a plurality of electrodes individually supported between adjacent ones of said spacer rings, and means for retaining said spacer rings and said electrode means within said shell.

18. 14. In an electron-discharge device, a unitary electrode assembly comprising, a cathode structure including a cathode and a member surrounding said cathode and having peripheral retaining means, a cylindrical shell of insulation material engaging said retaining means, a plurality of identical interchangeable ceramic spacer rings stacked upon said member within said shell, electrode means supported between predetermined adjacent ones of said spacer rings, and means for retaining said spacer rings and said electrode means within said shell.

19. 15. In an electron-discharge device, a unitary

electrode assembly comprising, a cathode structure including a cathode and a member surrounding said cathode and having peripheral retaining means, a cylindrical shell of insulation material engaging said retaining means, a plurality of identical interchangeable ceramic spacer rings stacked upon said member within said shell, a control electrode supported between predetermined adjacent ones of said spacer rings and having a dish-like configuration of a depth related to the width of said spacer rings to give the desired control electrode-cathode spacing, and means for retaining said spacer rings and said control electrode within said shell.

16. In an electron-discharge device, a unitary electrode assembly comprising, a cathode structure including a cathode and a member surrounding said cathode and having peripheral retaining means, a cylindrical shell of insulation material engaging said retaining means, a plurality of identical interchangeable ceramic spacer rings stacked upon said member within said shell, a plurality of electrodes individually supported between adjacent ones of said spacer rings, said electrodes having dish-like configurations of depths accurately predetermined to determine the electrode spacings of the assembly, and means for retaining said spacer rings and said electrodes within said shell.

17. In an electron-discharge device, a unitary electrode assembly comprising, a cathode structure including a cathode and a member surrounding said cathode and having peripheral retaining means, a cylindrical shell of insulation material engaging said retaining means, a plurality of identical interchangeable ceramic spacer rings stacked upon said member within said shell, a plurality of electrodes individually supported between adjacent ones of said spacer rings, said electrodes having dish-like configurations of different accurately predetermined depths and tapered sides to permit nesting thereof, thereby to provide electrode spacings much less than and independent of the width of said spacer rings, and means for retaining said spacer rings and said electrodes within said shell.

18. In an electron-discharge device, a unitary electrode assembly comprising, a cathode structure including a cathode and a member surrounding said cathode and having peripheral retaining means, a cylindrical shell of insulation material engaging said retaining means, a plurality of annular spacer rings stacked upon said member within said shell, electrode means supported between predetermined adjacent ones of said spacer rings, and an anode disposed within said shell beyond said electrode means.

19. In an electron-discharge device, a unitary electrode assembly comprising, a cathode structure including a cathode and a member surrounding said cathode and having peripheral retaining means, a cylindrical shell of insulation material engaging said retaining means, a plurality of annular spacer rings stacked upon said member within said shell, electrode means supported between predetermined adjacent ones of said spacer rings, and an anode disposed within said shell on the side of said electrode means opposite said cathode structure and including means for engaging said shell to retain said spacer rings and said electrode means therein.

20. In an electron-discharge device, a unitary electrode assembly comprising, a cathode structure including a cathode and a member surrounding said cathode and having peripheral retain-

ing means, a cylindrical shell of insulation material engaging said retaining means, a plurality of annular spacer rings stacked upon said member within said shell, electrode means supported between predetermined adjacent ones of said spacer rings, and an anode disposed within said shell on the side of said electrode means opposite said cathode structure and including a rigid terminal constituting a support for said assembly.

21. In an electron-discharge device, a unitary electrode assembly comprising, a cathode structure including a cathode and a member surrounding said cathode and having peripheral retaining means, a cylindrical shell of insulation material engaging said retaining means, a plurality of annular spacer rings stacked upon said member within said shell, electrode means supported between predetermined adjacent ones of said spacer rings, and a disk-like anode including a plurality of radially extending tabs for engaging said shell to retain said spacer rings and said electrode means therein, said anode being provided with a rigid terminal constituting a support for the assembly and being formed with a plurality of louvers to facilitate exhaust of the interior of the assembly.

22. In an electron-discharge device, a unitary electrode assembly comprising, a cathode structure including a cathode and a member surrounding said cathode and having opposed peripheral retaining means and a pair of electrode sub-assemblies disposed on opposite sides of said member, each comprising a cylindrical shell of insulation material engaging said retainer means, a plurality of spacer rings stacked upon said member within said shell, electrode means supported between predetermined adjacent ones of said spacer rings, and means for retaining said spacer rings and said electrode means within said shell.

23. In an electron-discharge device, a unitary electrode assembly comprising, a cathode structure including a cathode and a pair of opposed annular cup-shaped members surrounding said cathode, and a pair of electrode subassemblies disposed on opposite sides of said members, each comprising a cylindrical shell of insulation material seated in and frictionally engaging its respective cup-shaped member, a plurality of spacer rings stacked upon said member within said shell, electrode means supported between predetermined adjacent ones of said spacer rings, and means for retaining said spacer rings and said electrode means within said shell.

24. An electron-emissive cathode of the equi-potential type for an electron-discharge device comprising, an annular hollow conductive member having an electron-emissive coating on at least a portion of the surface thereof, and a heating element disposed within said member, said member being provided with a plurality of radially extending supporting tabs.

25. An electron-emissive cathode of the equi-potential type for an electron-discharge device comprising, an annular hollow conductive member having an electron-emissive coating on at least a portion of the surface thereof, a heating element disposed within said member, an annular supporting element surrounding said member, and thermal expansion means supporting said member from said supporting element.

26. An electron-emissive cathode of the equi-potential type for an electron-discharge device comprising, an annular hollow conductive member having an electron-emissive coating on at

least a portion of the surface thereof, and a heating element disposed within said member, an annular supporting element surrounding said member, and a plurality of semi-rigid wires bonded to said tabs and to said supporting element.

27. An electrode for an electron-discharge device comprising an annular metallic supporting member having a curved inner rim projecting from one face thereof, a wire screen covering the opening in said member and bonded to the periphery thereof, said screen extending over the inner surface of said rim and having a dish-like configuration.

28. An electron discharge device comprising a unitary electrode assembly including a plurality of electrodes each having a substantially circular central portion and supporting means extending from the edge of said central portion, a plurality of annular spacer rings of insulating material arranged in a stack with the supporting means of the various individual electrodes arranged between adjacent ones of said spacer rings, means including a pair of members engaging opposite ends of said stack for retaining said rings and electrodes in assembled relation, an envelope, and means engaging at least one of said members for supporting said electrode assembly within said envelope.

29. An electron discharge device comprising a unitary electrode assembly including a plurality of electrodes each having a substantially planar surface and supporting means extending from the edge thereof, a plurality of spacer rings of insulating material arranged in a stack with the supporting means of the various individual electrodes arranged between adjacent ones of said spacer rings, a substantially cylindrical enclosure for retaining said rings and electrodes in assembled relation including a pair of sheet metal members engaging opposite ends of the assembly, an envelope, and means engaging said cylindrical enclosure for supporting said electrode assembly within said envelope.

30. An electron discharge device comprising a unitary electrode assembly including a plurality of electrodes each having a substantially planar surface and supporting means extending from the edge thereof, a plurality of circular spacer rings of insulating material having a uniform outer diameter and arranged in a stack with the supporting means of the various individual electrodes arranged between adjacent ones of said spacer rings, means including a pair of sheet metal member engaging opposite ends of said assembly for retaining said rings and electrodes in assembled relation, an envelope, and means engaging at least one of said metal members for supporting said electrode assembly in spaced relation with respect to the interior walls of said envelope.

31. An electron discharge device comprising a substantially flat equi-potential cathode having an electron emissive coating on at least a portion of the opposite exterior surfaces thereof, said cathode having supporting means extending from the edge thereof, two stacks of insulating rings, one arranged on each side of said cathode and engaging said supporting means, a plurality of electrodes each including supporting means extending outwardly therefrom and individually received between adjacent ones of said spacer rings, a cylindrical enclosure for retaining said electrodes and said spacer rings in assembled relation including a pair of sheet metal members

engaging the outer ends of said stacks, an envelope enclosing said electrode assembly, and means engaging said cylindrical enclosure for supporting said assembly from said envelope.

32. An electron discharge device comprising a substantially flat equi-potential cathode having an electron emissive coating on at least a portion of the opposite exterior surfaces thereof, said cathode having supporting means extending from the edge thereof, a stack of insulating rings arranged on opposite sides of said cathode and engaging said supporting rings, a plurality of electrodes each including peripherally extending portions individually received between adjacent ones of said spacer rings, a cylindrical enclosure for retaining said electrodes and said spacer rings in assembled relation, an envelope enclosing said electrode assembly, and means engaging said cylindrical enclosure for supporting said assembly from said envelope.

33. An electrode assembly for an electron discharge device including a plurality of insulating spacer rings of uniform thickness arranged in a stack, a plurality of control electrodes each including a central planar portion and outwardly extending supporting means, the central portions of said electrodes being offset different distances with respect to the associated supporting means to produce desired spacing of the central portions of said control electrodes independently of the thickness of said spacers.

34. An electric discharge device comprising a unitary electrode assembly including a plurality of electrodes each having a central portion and a marginal supporting portion extending outwardly from the central portion, a plurality of annular spacer rings of insulating material arranged in a stack with the supporting portions of the various individual electrodes arranged between adjacent ones of said spacer rings, an envelope and a plurality of lead-in conductors sealed through said envelope and engaging said assembly of electrodes and spacers at opposite ends thereof to maintain said rings and spacers in assembled relation and to support said assembly in insulated relation with respect to the interior of said envelope in spaced relation with respect to the interior wall thereof.

WILLIAM S. BRIAN.
